UNITED STATES PATENT OFFICE.

ARTHUR LIPSCHUTZ, OF ST. LOUIS, MISSOURI.

TRUCK AND BODY BOLSTER.

SPECIFICATION forming part of Letters Patent No. 738,212, dated September 8, 1903.

Application filed December 4, 1902. Serial No. 133,857. (No model.)

To all whom it may concern:

Be it known that I, ARTHUR LIPSCHUTZ, a resident of the city of St. Louis, State of Missouri, have invented certain new and useful 5 Improvements in Truck and Body Bolsters, of which the following is a specification.

My invention relates to truck and body bolsters for railroad-cars; and the object of my invention is to provide a strong all-metal bolster of less weight and cost than the bolsters which are now in use devised or invented heretofore.

A particular object of my invention is to provide a truck or body bolster in which ordinary rolled or structural steel shapes—such as channel-bars, I-beams, and the like—may be employed without alteration in shape.

Another object of my invention is to provide a metal bolster comprising two parallel bolster members which though ordinarily combined in a single bolster, may be used independently, each as a light bolster.

My invention consists in a car-bolster comprising parallel rolled-steel beams suitably 25 fastened together and each having a truss comprising a solid web that is rimmed by a flange that follows the complete outline of said web, the long flange of the truss being in each case riveted to the flange of its respective 30 beam; and, further, my invention consists in various details of construction and in combinations of parts, all as hereinafter described, and particularly pointed out in the claims.

The invention will be more readily understood by reference to the accompanying drawings, forming a part of this specification, and in which—

Figure 1 illustrates a truck and a body bolster embodying my invention. Fig. 2 is a 40 cross-section of the body-bolster. Fig. 3 is a similar view illustrating a modification of the invention. Fig. 4 is a further cross-section of my bolster, showing I-beams in place of channel-beams; and Fig. 5 is a perspective 45 view of one of the individual trusses comprising my invention.

The most practical form of my invention includes a rolled channel 2 or a rolled I-beam 3, these being commercial shapes which can be 50 readily obtained in various sizes as required in the manufacture of bolsters for cars of dif-

ferent carrying capacities; but other and different beams and shapes may be utilized within the scope of my invention, though not economically adapted to bolster construction. 55 The gist of this invention resides in a pressed-steel individual truss having a continuous flange or rim riveted to the flange of each beam.

The simple bolster element of my invention 60 comprises a rolled channel 2 or a rolled I-beam 3 and a shorter truss 4, that is riveted to the lower flange of the beam, with its web 4' in alinement with the web of the beam—that is, in the same vertical plane. The truss 65 comprises said web 4' and the continuous flange or rim 4", the longest straight portion or side of which is applied to the flange of the beam.

As shown, the flange or rim of the truss conforms to or outlines the truss, which, as 70 shown, is of varying depth and is provided with a flat bottom 4'", that is a portion of the flange 4". In the case of a body-bolster the center plate is attached to said flat portion 4"". This simple bolster element, as 75 pointed out in a companion divisional application, is suitable for employment as a body-bolster for a light car and when equipped with column-guides, such as 5, is a very good truck-bolster for such a car, presenting a maximum 80 of strength in a minimum weight of material. The ordinary demand is for a heavier bolster, which I make by placing two of the described elements or simple bolsters back to back and securing the same by means such as the dia- 85 phragm-blocks 6 and the end straps 7, which may be of various designs and arrangements. This bolster may be strengthened by the addition of a cover-plate 8 and may be further strengthened by an intermediate plate 9, fas- 90 tened between the beam and their trusses. A still heavier bolster is made with I-beams 3 in place of the channel-beams. The truck-center 10 may be attached to the top of the truck-bolster and the center 11 to the bottoms 95 of the trusses of the body-bolster in any suitable manner.

It is obvious that numerous modifications of my invention will readily suggest themselves to one skilled in the art, and I therefore do not confine the invention to the specific 100 constructions herein shown and described.

Having thus described my invention, I claim as new and desire to secure by Letters Patent—

- 5 1. The bolster, comprising the parallel flanged beams, rigidly secured together and each provided with an individual pressed-steel truss, riveted to its lower flange and comprising a vertical web having a continuous flange or rim, substantially as described.
- 10 2. The bolster, comprising the parallel rolled-steel beams, having lateral flanges, in combination, with means rigidly securing said beams together, and, the individual trusses of said beams, each comprising a web of varying depth having a continuous flange or rim, the upper portions of said trusses being riveted
- 15

to respective beam-flanges, substantially as described.

3. The bolster, comprising the rigidly-connected parallel flange-beams, in combination, with a cover-plate riveted to the top flanges of said beams and the individual dished trusses, riveted to the bottom flanges of respective beams, substantially as described.

In testimony whereof I have hereunto set my hand this 29th day of November, 1902, at St. Louis, Missouri.

ARTHUR LIPSCHUTZ.
